US0D1113251S

(12) **United States Design Patent** (10) **Patent No.:** **US D1,113,251 S**
(45) **Date of Patent:** **** Feb. 17, 2026**

(54) **MATTRESS COVER**

(71) Applicant: **Sealy Technology LLC**, Trinity, NC (US)

(72) Inventors: **Alexa Meyer**, Chicago, IL (US); **Kara Pruitt**, Greensboro, NC (US); **Leigh Morrison**, Greensboro, NC (US); **Ali Bowen**, Lexington, KY (US); **Ivan Chavez**, Panorama City, CA (US)

(73) Assignee: **SEALY TECHNOLOGY LLC**, Trinity, NC (US)

(**) Term: **15 Years**

(21) Appl. No.: **29/824,158**

(22) Filed: **Jan. 21, 2022**

(51) LOC (15) Cl. **06-13**

(52) U.S. Cl.

USPC **D6/606**; D6/596

(58) **Field of Classification Search**

(57) **CLAIM**

The ornamental design for a mattress cover, as shown and described.

DESCRIPTION

FIG. 1 is a front elevational view of a mattress cover; FIG. 2 is a rear elevational view of the mattress cover of FIG. 1;

FIG. 3 is a left side elevational view of the mattress cover of FIG. 1;

FIG. 4 is a right side elevational view of the mattress cover of FIG. 1;

FIG. 5 is a top view of the mattress cover of FIG. 1; FIG. 6 is a bottom view of the mattress cover of FIG. 1; and, FIG. 7 is a perspective view of the mattress cover of FIG. 1. The broken lines shown in the drawings are included for the purpose of illustrating unclaimed portions of the mattress cover and form no part of the claimed design.

1 Claim, 5 Drawing Sheets
